UNITED STATES PATENT OFFICE

DUDLEY S. INGRAHAM, OF BRISTOL, CONNECTICUT, ASSIGNOR TO THE E. INGRAHAM CO.,
OF BRISTOL, CONNECTICUT, A CORPORATION

WRIST-WATCH CASE

Application filed June 5, 1929. Serial No. 368,460.

My invention relates to an improvement in cases for wrist-watches, the object being to provide a simple, compact and attractive wrist-watch case constructed with particular reference to convenience of the initial assemblage of the watch and its ready disassembly for attention to the movement as occasion may require. A further object of my invention is to produce a wrist-watch case in which the main members of the case are frictionally held together and also provide a high degree of efficiency in the matter of the exclusion of dust from the movement.

With these ends in view, my invention consists in a wrist-watch case comprising an inner and an outer case-member corresponding to each other in form and differentiated in size only enough to permit the inner member to be frictionally forced into the outer member and having certain details of construction as will be hereinafter described and particularly pointed out in the claim.

For the illustration of my invention I have shown it as applied to a wrist-watch of ordinary oblong form having rounded sides and flat ends but my invention is not limited to any particular form.

In the accompanying drawings:

Fig. 1 is a plan view of a wrist-watch case embodying my invention;

Fig. 2 is a side view thereof;

Fig. 3 is a view thereof in longitudinal section on an enlarged scale on the line 3—3 of Fig. 1;

Fig. 4 is a view in transverse section on the line 4—4 of Fig. 1;

Fig. 5 is a broken detail sectional view on the line 5—5 of Fig. 1;

Fig. 6 is a detached perspective view of the outer member of the watch-case; and

Fig. 7 is a similar view of the inner member thereof.

In carrying out my invention I employ an outer case-member stamped from a single piece of sheet-metal and comprising two complementary rounded side-flanges 10—10, two flat end-flanges 11—11, and a retaining-flange 12 extending inwardly from the outer edges of the said side- and end-flanges and forming the bezel of the watch-case. The said

end-flanges 11—11 are provided with perforations 13 spaced apart for the reception of the inwardly-turned ends of the two wire strap-loops 14—14 which are provided for the reception of the straps by which the watch is held upon the wrist of the user. The ends of the said strap-loops 14 are passed through the perforations 13 and headed down upon the inner faces of the said flanges 11—11. The inner case-member comprises two rounded complementary side-flanges 15—15, two flat end-flanges 16—16 and a flat integral bottom 17 integral with the outer edges of the said side- and end-flanges, this inner case-member being just enough smaller in its exterior dimensions to permit it to be telescoped into the outer case-member with a friction dust-excluding fit. Its end-flanges 16—16 are formed, as shown, with spaced-apart clearance-notches 18 to clear the headed terminals of the inwardly-turned ends of the two strap-loops 14—14. The end-flanges 16—16 are also formed with perforations 19 for the reception of screws (not shown) for the retention of the movement which is installed within the inner case-member but the mode of installation of the movement forms no part of the present invention.

As shown, one of the rounded side-flanges 15—15 is formed with a clearance-notch 20 to receive the winding-stem of the watch-movement, the corresponding flange 10 of the outer case-member being furnished with a registering perforation 21 for the same purpose.

As shown, for supplementing the frictional coupling of the two case-members, the two end-flanges 11—11 of the outer member are formed near their edges with retaining-grooves 22 receiving ribs 23 struck out from the two end-flanges 16—16 of the inner member, as clearly shown in Fig. 5.

For the retention of the non-breakable crystal 24 in place the depth of the two cup-shaped case-members is so proportioned that when they are telescoped together into their "home" positions, after introducing the said crystal into the bottom of the outer case-member, the edges of the flat end-flanges 16—16 of the inner case-member engage with the ends of the crystal and force the same

against the inner faces of the ends of the retaining or bezel flange 12 of the outer case-member. As shown, the ends of the crystal are set inward to form shoulders 25 against which the end-edges of the retaining-flange or bezel 12 abut, as shown in Fig. 5, but this is not a necessary part of my improvement.

I claim:

In a wrist-watch case, the combination with
10 a cup-shaped one-piece outer case-member of which the side- and end-flanges merge at their outer edges into an integral inwardly-extending bezel; of a cup-shaped one-piece inner case-member of which the side- and end-
15 flanges merge at their outer edges into a bottom integral with them, and the said end-flanges being formed with clearance-cuts, and the said members being adapted in form and dimensions to permit the inner case-member
20 to be telescoped into the outer case-member, a crystal corresponding in shape to the said members and set within the outer case-member in position to have its ends clamped directly between the inner faces of the ends of
25 the said bezel of the said outer case-member and the inner edges of the end-flanges of the said inner case-member; and outwardly-projecting strap-loops riveted in the end-flanges of the said outer case-member and also projecting inwardly therethrough and entering the said clearance-cuts in the said inner case-member.

In testimony whereof, I have signed this specification.

35 DUDLEY S. INGRAHAM.
